UNITED STATES PATENT OFFICE.

HERBERT RASMUS JENSEN, OF WHAKARONGA, NEW ZEALAND.

MOLE DRAIN PLOW.

Application filed September 24, 1926. Serial No. 137,572.

My invention relates to mole drain plows, a type of implement used by farmers and others to make underground drains for the purpose of draining waterlogged, sour land 5 and the like, thus making the said land more easy to work and consequently more productive.

The object of the present invention is to provide an improved type of mole drain plow 10 which though of light construction and draught is simple and efficient in operation, as the implement can be handled and placed in position with a minimum of labour, and is strong enough to do all the work required 15 of it.

A further object of my invention is to provide means whereby the plow can be automatically adjusted to various depths while in the ground to give an even grade in the 20 drain; this is especially advantageous when draining ground having rises and depressions.

A still further object of the invention is to provide means whereby the plow is adapted to automatically leave the ground when 25 the drain is finished.

I make reference to the drawings accompanying this specification in which:—

Figure 1 is a side elevation of the invention, the ground level being indicated by dotted 30 lines.

Figure 2 is a plan view of Figure 1.

Figure 3 is a plan view on the line B—B Figure 1, to more clearly illustrate the construction of the torpedo and the mole plug. 35

Figure 4 is a section on the line A—A, Figure 1, illustrating the light frame construction.

Figure 5 is a view of the stay.

Figure 6 is a view of the ratchet mechanism to alter depth of plow.

In the construction of my invention I employ two angle iron members 1 and 1^A fitted together by bolts 2 having distance pieces 3 thereon.

Attached to the front end of the said angle iron members are what may be termed two suitably shaped metal skids or runners 4 which are positioned far enough apart from each angle iron member 1 and 1^A to prevent 50 tilting of the plow.

The method of attaching the said skids or runners 4 to the angle iron members 1 and 1^A is clearly illustrated in Figure 2 of the accompanying drawings. The said skids or 55 runners 4 are preferably curved and dished as illustrated to assist the plow in riding

over the ground and to give the beam members a clearance.

Suitable means are provided such as a shackle or link 5 and chain 6, attached to the forward end of the members 1 and 1^A by the said bolt 2 and distance piece 3 whereby a horse team or power tractor may be attached to the plow. According to this invention a blade member 7 is provided, constructed of 60 special steel, of sufficient thickness and pivotally connected to the rear end of said angle members 1 and 1^A by a pin or bolt 8, the front edge of the upper portion of the blade is formed with a series of notches 9 for the purpose hereinafter described, while the lower end of the blade 7 has its forward end formed into a knife shaped edge; the upper extremity of this knife shaped edge is slightly curved 70 forward as indicated in Figure 1.

There is a torpedo member 10 provided which is riveted to the bottom of the blade as indicated in Figure 1 of the drawings at such an angle so as to give an undercut or slant 80 to the blade and thus help to keep the plow at its set depth. A mole plug 11 is provided and pivotally attached to the rear end of the torpedo, preferably by means of a knuckle joint 12, the said mole plug 11 to have a hole 13 through it, to allow air to pass down the 85 cut after the blade of the plow has got into the drain.

There is a stay member 14 provided preferably of tubular construction, the said stay is pivotally attached in a suitable position 90 between the angle irons 1 and 1^A forming the beam of the plow. The free end of the said stay 14 is shaped as illustrated in Figure 5 to permit of it engaging with the before mentioned series of notches 9 on the 95 blade 7 (see Figure 1), the angle of engagement being preferably about 45 degrees to permit a downward thrust to the frame, thus giving great strength and obviating shearing and additional bolts in attaching the blade 100 member 7 to the angle irons 1 and 1^A forming the beam of the plow and thus making it possible to use a metal of light construction.

To regulate the draught of a plow to a predetermined depth, the operator will require to unloosen bolt 8 and move the blade 7 until either of the holes 15 coincide with the holes in the frame members 1 and 1^A, then replace bolt 8 clamping blade to frame and at the same time adjust the stay 14 in the notches 110 9 formed on the blade 7 to give the said blade its required slope or angle to ensure that the

torpedo 10 fixed to the extremity of the blade 7 provides the requisite angle for the undercut.

Mounted upon the side of one of the angle members 1 or 1^A is a handle 16 for lifting the rear end of the plow and suitably positioned on said stay 14 is a handle 17 whereby the said stay is adapted to be engaged and disengaged as required from the notches 9 on the 10 blade 7.

In Figure 6 is illustrated a means by which the angle of the said blade 7 and torpedo 10 can be set as will vary the grade of the drain or cause the torpedo 10 to cut the said drain 15 to the surface of the ground 18. This object is accomplished by attaching a quadrant 19 to the centre bolts 2 of the angle iron frame members 1 and 1^A and by the use of a suitably mounted lever 20 provided with a trigger 21, 20 connecting link 22 and spring bolt 23 engaging with the rack 24 of the said quadrant 19; one end of the said lever being bell cranked and one end being pivoted on bolt 2, the other end 25 of the bell crank lever being attached 25 to the stay 14 by means of a bolt 26. The lever 20 will be of sufficient length so that it can be operated by the driver of the horse team or power tractor hauling the plow. The trigger 21 and spring bolt 23 may be of the 30 design in common use.

Referring again to blade 7 fitted between the said angle irons 1 and 1^A this blade has a four fold purpose, (1) the top end of blade acts as a lever when supported by the stay 35 14 against the lower end which draws mole plug 11 (2) the top end of blade 7 acts as a ratchet having notches 9 into which the stay 14 is set being the depth regulator (3) when the stay 14 is released from blade 7 and plow 40 drawn forward, the top corner 27 of the blade 7 catches in ground and turns the blade over so that the mole plug 11 rests on top of beam, and the top rounded side 28 of blade 7 then acts as a runner to carry back end of 45 plow when out of action.

The position of the bolt 2 supporting the lower end of stay 14 is such as will permit of the upper portion of the said blade 7 revolving past said bolt 2 when the mole plug 11 is 50 being withdrawn.

In operation draw the plow to where the outlet of drain is to be, using a chain of suitable length so that the front of plow is not lifted off the ground when working; take 55 hold of handle 16 with the left hand and with the right swing the blade 7 around so that the torpedo 10 rests on the ground, set into bank of open drain or elsewhere, pull the regulator stay 14 over and set into any of the required

notches 9 on the blade 7 using the higher 60 notches for deep depths and the lower ones for shallow depths. To alter the depth of the plow pull the top of blade 8 back a little to release the stay 14 and then reset it, the plow will then run gradually to the depth 65 set. When the drain is finished release the stay 14 throw it forward, draw the plow forward and this causes the blade 8 to leave the ground and turn over, the top of the blade 70 then acts as a runner to carry the back of the plow.

From the foregoing description it will be apparent that there is thus provided a device of the character described possessing the 75 particular features of advantage before enumerated as desirable, but which obviously is susceptible of modification in its form, proportion, detail construction or arrangement of parts, without departing from the principle involved or sacrificing any of its advantages.

What I claim as new and desire to secure by Letters Patent is:—

1. An improved mole drain plow comprising two angle iron members suitably joined together forming the beam of the plow, runner members or skids attached to the forward end of each angle iron member, an adjustable blade member suitably retained between the said angle iron members and near the rear end thereof, the said blade having a series of notches on its front edge and a knife shaped edge on its lower extremity, a torpedo member attached to the lower end of said blade, provided with a pivotally mounted mole plug, 90 an adjustable stay member mounted between the said angle iron members adapted to engage with the said notches on the said blade, and means by which the angle of the said blade and torpedo can be adjusted as 95 herein described and as illustrated.

2. An improved mole drain plow according to claim 1, the said runner members or skids characterized by being curved or dished for the purpose specified and as illustrated. 105

3. A mole drain plow comprising a beam, a mole blade member mounted at the rear of the beam, said member having a series of teeth on its front edge above the beam, and having its front edge sharpened below the 110 beam, a torpedo attached to the lower end of the blade member, a perforated mole plug at the rear end of the torpedo, and means between the beam and the toothed front edge of the blade member to hold the blade member in adjusted position.

In testimony whereof I affix my signature.
HERBERT RASMUS JENSEN.
